[57] CLAIM

The ornamental design for an infant automobile seat, as shown and described.

DESCRIPTION

FIG. 1 is a front perspective view of a infant automobile seat, showing our design;

FIG. 2 is a top plan view;

FIG. 3 is a front elevational view;

FIG. 4 is a left side elevational view, the right side elevational view being a mirror image thereof;

FIG. 5 is a rear elevational view; and

FIG. 6 is a bottom plan view thereof.

FIG. 1.

FIG. 2.

FIG. 5.

FIG. 4.

FIG. 3.

FIG. 6.
